UNITED STATES PATENT OFFICE

LOUIS H. MORIN, OF NEW YORK, N. Y., ASSIGNOR TO DOEHLER DIE-CASTING CO., A CORPORATION OF NEW YORK

REMOTE CONTROL FOR RADIO TUNING DEVICE

Application filed February 1, 1930. Serial No. 425,082.

This invention comprehends means to tune a radio receiving set and vary the volume of the sound emitted from the loud speaker associated therewith at a point remote from the set. It has a special application to sets which are equipped with automatic tuning devices and in some respects constitutes an improvement in the devices shown in my copending applications, Serial No. 384,831 and Serial 10 No. 407,381 filed August 10, 1929 and November 15, 1929 respectively, the latter application having issued as Patent No. 1,856,781 of May 3, 1932. In its broad aspect, the invention is independent of any particular 15 form of automatic tuner device, although specifically, the embodiment which I have selected for illustration is particularly designed to function with the form of automatic tuner which constitutes the subject matter of my 20 copending application, Serial No. 355,190, filed April 15, 1929.

Automatic tuners avoid the necessity of a delicate or very particular adjustment of the dials in order to tune a radio receiving set 25 into resonance with any selected wave, and enable one to effect a selective tuning by the performance of a simple mechanical operation that requires no delicacy of control. For this purpose they have a plurality of manually controlled actuating members which are 30 operatively related to the movable part of the tuning element of the set and which are independently adjustable with respect to such relationship. Each actuating member is thus 35 so set that when manually operated it will bring the tuning element into resonance with a particular wave length.

In the form of automatic tuner illustrated in my said copending application Serial No. 40 355,190, the actuating members which are adjustable with respect to the movable member consist of single toothed pinions frictionally mounted upon an operating shaft and adjustable angularly thereon. The operating 45 mechanism consists of a pair of ring gears disposed side by side and fitting over the pinions, and slidably longitudinally of the shaft selectively into register with the pinions. The ring gears have external gear teeth and each 50 has a single internal tooth, and suitable means,

such as a rack, is employed to operate the gears in opposite directions. The internal gear teeth will be stopped in their rotation when they are both in engagement with the pinion tooth but on opposite sides thereof. 55 In order to tune the set to any station corresponding to one of the single toothed pinions, the rack with its ring gears is moved laterally into register with that pinion and the rack is then moved longitudinally so as 60 to rotate the two ring gears until their internal teeth engage on opposite sides of the single tooth of the pinion. This lateral shifting and longitudinal actuation of the rack is effected manually. 65

In the form of remote control shown in my copending application Serial No. 384,831, a motor is connected to effect the same movements of the rack and ring gears when a manual switch is operated at the remote point. 70 The transmission between these elements and the motor for the effecting of the lateral shifting includes a shifting device which is rotatable upon a shaft parallel to that upon which the pinions are mounted and is also slidably 75 longitudinally thereon, and this shifting device is operatively connected through a pivoted lever to the housing for the ring gears, whereby a lateral movement of the shifting device is transmitted to the ring gears and 80 rack. This shifting device has an oblique cam face on its peripheral surface and the rotary movement which is imparted to the shifting device by the motor is translated into a lateral or axial movement by a plurality of 85 abutment pins which are selectively insertable into the path of the cam face. The extent of the axial shifting of the device depends upon which pin is inserted and this in turn is 90 controlled by the manual switch device at the remote control point. 95

For longitudinal actuation of the rack by the motor a pivoted lever is connected for reciprocation by the motor and is of sufficient width to engage an abutment upon the rack in any position of lateral adjustment of the rack and associated parts.

The improved transmission for the effecting of the lateral shifting and subsequent operation of the operating means shown in my 100

copending application, Serial No. 407,381 above referred to, which is the transmission of the present invention with some improvements therein, includes a screw shaft which is rotatable in bearings provided therefor. A nut having internal projections corresponding to the thread of the screw shaft is fitted thereover so that rotational movement of the shaft advances the nut longitudinally of the shaft. The nut is secured to the housing for the ring gears whereby lateral movement of the nut is transmitted to the ring gears and the rack. This shifting of the ring gears and rack is governed by a plurality of abutment levers which are selectively insertable into the path of the housing for the ring gears. The extent of the lateral shifting of the housing depends upon which pin is inserted, and this in turn is controlled by the manual switch device at the remote control point.

The actuation of the ring gears is effected by a gear secured to the nut on the screw shaft to rotate therewith, and the nut rotates with the screw shaft when its further lateral movement is restrained by an abutment pin. Specifically, the nut is journaled in the housing for the ring gears. As the screw shaft is rotated the nut advances along the shaft and abuts against the side of the gear housing, thereby moving the housing laterally. When the housing strikes the abutment pin inserted in the path thereof, further lateral movement is restrained and the internal projections on the nut wedge in the threads of the screw shaft to rotate the nut therewith. Rotation of the nut rotates its gear with it, and this gear not only rotates one of the ring gears but also rotates a pinion which meshes with it and which also meshes with the rack, thereby effecting a longitudinal movement of the rack.

When the tuning of the set is completed and the screw shaft is released by action of the automatic clutch, the gear housing is returned to its original position by means of a spring.

In connection with the above described tuning mechanism, I have in accordance with the present invention provided a movable member which is operatively connected to affect the volume of the sound emitted from the sound reproducing element associated with the set. A single power device is utilized to operate the tuning mechanism and the volume control. The power device is selectively connectible to the transmission of the tuning device and to the movable member operatively connected to affect the volume of the sound emitted from the sound reproducing device for the operation thereof.

Specifically, the motor for supplying power to operate the automatic tuning device is connectible to the power transmission mechanism for operating the automatic tuner through an electromagnetic clutch. Associated with the magnetic clutch and actuated

thereby, there is a selector device for connecting the motor to and disconnecting the motor from the movable member operatively connected to affect the volume of the sound emitted from the sound reproducing unit. Normally, the motor is connected to the movable member operatively connected to vary the volume, and the selector device is actuated to disconnect the motor therefrom upon the energization of the electromagnetic clutch to connect the motor to the power transmission mechanism for operating the automatic tuner. The energization of the motor to cause it to operate the movable member connected to vary the volume in one direction to increase the volume and in the opposite direction to decrease the volume, and the energization of the electromagnetic clutch to connect the motor to the power transmission mechanism for operating the automatic tuner are controlled by the manual switch device remote from the receiving set.

A normally closed switch, through which the circuit from the receiving set to the sound reproducing unit is completed is so located with respect to the magnetic clutch that it is opened by the operation of the clutch to connect the motor to the power transmission mechanism for operating the automatic tuner, thereby breaking the circuit to the sound reproducing unit while the receiving set is being tuned.

Various other particulars of the invention will appear from the following description of the illustrated embodiment.

Fig. 1 is a side elevation partly in section of an embodiment of the invention installed in a cabinet, the front panel of which is shown in section;

Fig. 2 is a vertical section through the automatic tuning portion of the mechanism taken on the irregular line 2-2 of Fig. 1;

Fig. 14 is a detail of an element constituting a contact bar;

Fig. 15 is a detail of an element constituting the lower series of switches; and

Fig. 16 is a wiring diagram of the electrical connections.

The movable member of the automatic tuner, which is the part that carries the manually actuatable devices that are adjustably related thereto, is operatively connected in any suitable way with the tuning elements or resonance-varying devices of the receiving set. In the illustrated construction this movable member is a shaft 1 and the tuning element is a variable condenser 2, only a portion of which is shown and which is supported in the cabinet by a bracket above the tuning mechanism. The operative connection consists of the two pulleys 3 and 4 on one end of the shaft 1 and a pulley 5 on the condenser shaft which are connected by a cord belt 6, the ends of which are connected to the peripheries of the pulleys 3 and 4 and which run over the idlers 7 and 8 intermediate of the pulleys, these idlers being secured in brackets on the base plate 9. The rotation of the shaft 1 is thus transmitted to the condenser 2.

The shaft 1 is journaled in side frame members 10 and 11 and is provided with four keyways 1a along an enlarged intermediate portion, as shown clearly in Fig. 1. Mounted upon this enlarged portion of the shaft are a plurality, shown as ten, of pinions which are numbered from 12a to 12j, inclusive. These pinions are each provided with a single tooth 13 and are loosely mounted upon the shaft. Between the pinions are friction discs 14 keyed to the shaft, and a friction disc is also provided at each end of the pack, the disc 14a being at the left end and the disc 14b being at the right end. The engaging faces of the discs and pinions are beveled, the pinions having a widened periphery and the discs having a narrowed periphery. In this way, the tooth 13 is made wider than the hub of the pinion so as to provide a fairly broad engaging face for the teeth on the actuating gears.

A clamping nut 15 screws on the right end of the shaft 1, which is threaded for this purpose, and this nut is provided at its outer end with an integral spur gear 16 with which meshes a pinion 17 on the stub shaft 18. This stub shaft is disposed parallel to and in front of the main shaft 1 and bears at its outer end 63 in the side frame 11 and at its inner end in a

bracket 19 formed on the upper edge of a casting 20. A beveled gear 21 on the inner end of the stub shaft 18 meshes with a beveled gear 22 on a stem 23 which bears in a rear bracket 24 and a bushing 25 formed on the casting 20 and extending into the front wall of the cabinet. The stem 23 projects through the front wall of the cabinet. A knob 27 on this stem 23 affords means for manipulation of the gear train just described, the knob being, in this manner, brought to the central vertical line of the panel.

Through this connection the turning of the knob 27 serves to back off and screw up the clamping nut 15 and thereby release and unclamp the pinions. Three coil springs 28, one of which is shown in Fig. 3, are seated in recesses in the inner face of the clamping nut 15 and these springs at all times bear against the outer face of a washer 29 on the shaft 1 immediately adjacent the friction disc 14b and thereby serve to exert a light frictional pressure upon the pack even when the nut 15 is backed away. This pressure is to hold the pinions sufficiently in frictional engagement with the shaft to prevent their displacement accidentally during the setting of any one pinion.

Back of the clamping nut 15, the shaft 1 has an abutment 30, which is shown as a collar fixed upon the shaft. This abutment permits of just enough travel of the nut to clamp and release the pinions. The engagement of the nut against the abutment 30 serves to lock the nut to the shaft against relative rotation. In this way, the nut 15 is connected to rotate the shaft 1 and hence the movable part of the tuning element 2 when the pinions are unclamped and free to be turned upon the shaft 1. It will also be observed that when the nut is in its clamping position, it is frictionally locked to the shaft through the friction discs and pinions and that, therefore, the knob 27 may be employed to adjust the tuning element in both positions of the clamping nut.

The outer friction disc 14a has a lateral stop projection 14c, which cooperates with a flange 10a on the inner face of the side plate 10 to limit the rotation of the shaft 1. When it is desired to back off the nut 15, the knob 27 is turned in a proper direction until the stop members 10a and 14c engage, whereupon further rotation of the shaft 1 is prevented and the continued turning of the knob serves to feed the nut in backward direction until it engages the abutment 30. When the knob is thereafter turned in the opposite direction, the shaft 1 will turn with it due to the frictional engagement between the nut and the abutment 30 until the shaft reaches its opposite limit of movement. Thereafter further turning of the knob will serve to feed the nut forward and clamp the pinions and friction discs together.

The manual operating elements are shift-

able into engagement selectively with any one of the pinions. They are carried by a support which consists of a two-part casting 31. This casting has a hub portion 32 at its front end 5 which slides upon a transverse guide rod 33, and is also provided with jaws 34 which slide upon a rear transverse rod 35 the upper jaw carrying a roller 36 which bears upon the rod 35. This casting has a downward annular 10 projection 37 which axially surrounds the shaft 1 and the parts mounted thereon. The inner faces of the two halves of the annular portion of the casting are recessed and within this recess with their axes in line with the 15 annular part 37 of the casting are two annular gears 38 and 39, each gear having on its outer lateral face a flange 40, which fits within the inner peripheral face of the extension 37 of the casting as a bearing. These 20 two gears have their inner faces contiguous and together are slightly wider than the face of a pinion 12 and the tooth 13 thereon. The outer periphery of the gears is provided with gear teeth and each gear has on its inner periphery a single tooth 41. The inner diameter of the gears is such that the teeth 41 will strike the tooth 13 of any pinion as they are rotated about that pinion.

On the upper part of the casting 31 at the 30 top of the recess between the two inner faces of the halves is slidably disposed a rack 42 which runs from front to rear of the casting and has its front end protruding out through a horizontal slot in the front panel of the 35 cabinet. On this front panel is secured a knob 43, back of which is an index pointer 44, the rear part of which extends through the slot back of the knob and is secured to the front face of the casting. The rack 42 has 40 operative connection with both gears 38 and 39, the width of the rack equaling the combined width of the two gears. This connection is such that the movement of the rack rotates the two gears in opposite directions. 45 For this purpose the rack is shown as geared to the gear 39 through a single pinion 45, and as geared to the gear 38 through the two pinions 46 and 47.

A convolute spring 48 serves to retract the 50 rack 42 after it is withdrawn by hand to effect a tuning operation. This spring is attached at one end to the rear end of the rack 42 and is bent around an idler pulley 49 on the rear of the casting and is connected at its other 55 end to a pin on the casting below the jaws 34. A decorative escutcheon plate 50 is disposed on the front panel above the slot in the panel through which the rack extends and slides, and in this escutcheon plate immediately 60 above the slot there is secured a strip 51 on which are marked the initials of the several stations to which the set may be automatically tuned. Back of this strip is a transparent 65 opening at the rear of which is a light 52 for interior illumination of the strip. The top

of the guide shaft 33 is provided with a series of notches 53, which notches register with the initials of the several stations on the strip 51, and these notches are in direct alignment with the several pinions 12. A bifurcated 70 bell crank lever 54 is pivoted to the hub 32 of the casting 31 directly above the rack 42. Journaled between one pair of arms of the lever 54 there is a cam roller 55 which is held in contact with the top of the rack 42 by a convolute spring 56. To the other pair of arms of the bell crank lever there is secured a lateral extension 57 which is adapted to register with the appropriate notch 53 in the top of the guide shaft 30 when the rack is 80 pulled out. A strip 58 on the top of the rack 42 is of a height to raise the cam roller 55 sufficiently to depress the extension 57 into the notches in the top of shaft 33 when the rack is pulled out, and the strip is of such a length that it terminates just back of the cam roller 55 when the rack is retracted. 85

Each pinion is set in proper position to bring the tuning mechanism and the receiving circuit into resonance with the particular station which the pinion represents, in the following manner: The knob 27 is turned so as to back off the nut 15 and releases the compression upon the elements on the shaft 1. The springs 28 continue to exert a pressure upon the elements so as to hold the pinions against turning until positive force is brought to bear upon them. If it be desired, for example, to set the pinion 12g so that its actuation will tune the set to WAAM, the knob 43 with the rack and other parts carried by the casting 31 are moved over to register with the slot 53 registering with the station WAAM, which is the position of the parts shown in Fig. 3. The rack 42 is then withdrawn. This movement rotates the gears 38 and 39 in opposite directions and the teeth 41 cooperate to move the tooth 13 on the pinion 12g to the position where the teeth 41 meet. The pinion is thus locked in this position. Due to the releasing of the clamping pressure of the nut 15, the shaft 1 may now be turned within the pinion 12g and the pinion 12g will be restrained from rotation by engagement of the teeth 41 with the tooth 13. The other pinions will, however, turn with the shaft without altering their angular relation thereto due to the pressure of the springs 28. In order to turn the shaft 1 within the pinion 12g and thereby tune the set to WAAM, the operator has only to turn the knob 27, for the nut 15 is now locked to the shaft 1, as above explained, by reason of the engagement of the nut 15 and the abutment 30. When the set is tuned to station WAAM, the operator will release the rack and further turning of the shaft 1 by the knob 27 will thereafter carry the pinion 12g with the shaft without changing its angular relation thereto. The operator will, therefore, turn the knob until 115 120 125 130

the shaft 1 reaches the limit of its movement, after which further turning of the knob will screw up the nut 15 and positively clamp the pinion 12g to the shaft. The nut is thereby 5 also locked to the shaft by reason of its frictional engagement with the washer 29, and the operator may use the knob 27 for tuning the set and at the same time the rack-operated parts may be used for automatically tuning 10 the set to any one of the ten stations represented by the ten pinions.

It will be understood that the steps above described for setting the pinion 12g will be repeated with all of the other pinions, the set 15 being tuned to the respective stations which the several pinions represent. Whenever the gears 38 and 39 are moved into register with any pinion and the rack is withdrawn, that pinion will always be moved to the position 20 which it occupied when it was set with respect to the shaft 1 and it will, therefore, always move the tuning element to the proper position to tune the set to the station which it represents.

25 The mechanism so far described is the automatic tuning mechanism of my said copending application Serial No. 355,190 with certain improvements which constitute the subject matter of my copending application 30 Serial No. 377,709. I shall now describe the remote control part of the mechanism. This in the main comprises means acting upon the automatic tuner to cause it to do automatically what the operator does manually by 35 manipulating the knob 43. In other words, the illustrated embodiment of my invention causes the rack 42 to travel laterally to bring the pinion representing the selected station and 40 then to move longitudinally in an outward direction and actuate the pinion 12 to bring the set into resonance with the selected station.

45 Power is delivered to the mechanism for the automatic operation by an electric motor 59 which is attached to the base plate 9, rubber washers being interposed to deaden the sound and cushion the vibration. This motor is connected through a train presently to be 50 described to a transverse screw shaft 60 bearing in the side frame member 10 and a thrust bearing 61 secured to the side frame member 11. The shaft 60 extends through a hub portion of the pinion 47 which is journaled in 55 the casting 31 and constitutes the aforementioned nut. This pinion bears against the side of the casting through a thrust bearing 62. Internal projections 63 are formed on the nut portion of the pinion 47 and fit in the 60 threads of the screw shaft 60. Clockwise rotation of the shaft 60, as viewed in Figure 1, will advance the pinion along the shaft, and the pinion bearing against the side of the two part casting will move the casting laterally, rotation of the pinion being restrained 65

by the friction of the train, connecting it to the rack 42.

The normal position of the rack is at the right, as shown in Figure 2, or as viewed from the front of the cabinet, to which position it 70 is resiliently urged by a convolute spring 64. The spring 64 is secured at one end to the hub 32 of the casting 31 surrounding the rod 33 and is bent around an idler pulley 65 on the side frame member 11 and connected at 75 the other end to the side frame member 11 near the base thereof. The distance the rack will be moved laterally from the normal position by rotation of the shaft 60 is determined by abutment levers 66 which are insertable 80 into the path of the casting 32. There are in all nine abutment levers, one for each of the pinions 12a to 12i, the abutment for the pinion 12j being a stop shoulder 67 on a slotted abutment guide member 68 formed 85 on the casting 20 in the slots of which the ends of the levers 66 are received. Each lever is controlled by a solenoid 69. The levers are pivotally supported in slots 70 formed in the casting 20. The solenoids 69 90 are supported on the base plate 71, on opposite sides of the guide member 68, the solenoids being disposed, five on one side and four on the other side of the member 68 in two staggered rows of three and two on one side and two and two on the other. The slots in the casting 20 in which the abutment levers are pivotally mounted are disposed intermediate the solenoids and the member 68. 95

The normal position of the levers 66, to which they are resiliently urged by springs 72, is that position in which the abutment end of the levers is withdrawn out of the path of the casting 31, and the opposite end is suspended above the solenoids 69. When the casting 31 reaches the abutment lever inserted in the path thereof or the shoulder 67, further movement of the pinion 47 longitudinally of the screw shaft 60 is restrained. Consequently, the internal projections on the pinion wedge against the side of the threads in the screw shaft 60 and the pinion rotates with the shaft, thereby rotating the annular gear 38 and causing longitudinal movement of the rack 42 through the pinion 46, which movement of the rack rotates the 130

annular gear 39 through the pinion 45 in a direction opposite to that of the gear 38. When the instrument is tuned and the shaft 60 is released, the casting 31 is returned to its initial position by the aforementioned spring 64, the rack being retracted by the spring 48.

The pinion 46 is mounted upon a square shaft 75 which is journaled at one end in the side member 10 and threaded at the other end in an opening in the side member 11, the pinion 46 being adapted to be moved longitudinally of the shaft and be secured there-to against relative rotational movement. On the side member 11 there is secured a switch 76 having a movable member 77 and stationary member 78, the two members being insulated from each other and from the casting by insulating material 79. The switch 76 is secured to the side member 11 of the casting by screws 80. The movable member of the switch is directly in line with the end of the square shaft 75 so that when the shaft is rotated by the pinion 46 and is moved longitudinally by virtue of its threaded connection with the side member 11, the end thereof will abut against the movable member 77 of the switch and close the switch. The movement of the shaft is such that the switch will be closed when the rack has reached its outermost position and the set is tuned.

The motor 59 is connected to the shaft 60 through reduction gearing and an electro-magnetic clutch. The shaft of the motor is coupled to a shaft 81 through a gear train 82. The shaft 81 bears in a two part casting 83 and on the inner end thereof within the casting a worm 84 is secured thereto for rotation therewith. The worm 84 meshes with a worm gear 85 secured to the reduced end of a shaft 86 which bears in the casting 83. The shaft 86 extends through a partition wall 87 within a compartment 88 formed in the casting 83. The end of the shaft 86 within the compartment 88 is enlarged and constitutes the core of an electromagnet 89, the casing 90 thereof which constitutes a pole of the electro-magnet is secured to the shaft 86 by means of a set screw 91. Around the casing of the electro-magnet, there are two collector rings 92 and 93 insulated from the casing and each other by a strip of insulating material 94. These collector rings are connected to the coil of the electromagnet and are energized by brush contacts 95 similar to ordinary brush contacts of a motor. The inner or active end of the electromagnet is adjacent to and in alignment with the screw shaft 60 of the automatic tuning mechanism. To the end of the screw shaft 60 adjacent the electro-magnet, a collar 96 having an arm 97 is secured by means of a set screw 98. A pin 99 movably mounted in a bushing formed on the outer end of the arm 97 is secured to a disc 100 which lies within the field of the electro-magnet 89. The disc 100 is resiliently urged away

from the face of the electro-magnet by a spring 101 acting between the arm 97 and an abutment plate 102 secured to the pin 99. Adjacent the opposite end of the shaft 86 journaled in another section 103 of the casting 83 there is a stub shaft 104 having a flange 105 formed at one end thereof and bearing against the outer end of the bearing formed in the casting, and a worm 106 formed on the end adjacent the shaft 86 and bearing against the inner end of the bearing formed in the casting. The shafts 86 and 104 are in alignment and are bored to receive a rod 107 which extends through the two shafts and is connected to the disc 100 to be moved thereby. Intermediate the shafts 86 and 104 there is a collar 108 fixed to the rod 107 and constitutes the selective element of the clutch device. The collar 108 is provided at each end with projections 109 and 110 which are received in notches 112 and 113 in the ends of the stub shaft 104 and the shaft 86 respectively. The projection 109 and its complementary slot 112 are substantially longer than the projection 110 and the slot 113 and are of such length that the projection 109 and the slot 112 are always in engagement. The projection 110 and its complementary slot 113, however, are of such length that when the disc 100 is attracted to the electro-magnet to couple the shaft 60 to the shaft 86 the projection 110 and its complementary slot 113 are out of engagement, thereby disconnecting the shaft 104 from the shaft 86.

The worm 106 formed on the shaft 104 meshes with a worm gear 114 loosely mounted upon a shaft 115 which bears in the section 103 of the casting 83. To the shaft 115, there is secured a bearing collar 116 which abuts against the side of the bearing in which the shaft 115 is journaled. Abutting against the opposite bearing, there is a plate 117 secured to the shaft 115. Between the plate 117 and the worm gear 114, there is a convolute spring 118 which resiliently urges the worm gear 114 into frictional engagement with the bearing collar 116. At one end of the shaft 115 which extends outside of the casting 83, there is secured for rotation therewith, a pulley 119 which is connected by means of a belt 120 to the movable element of the volume control 121. A knob is also secured to the movable element of the volume control for manual control of the volume, the gear 114 being loosely mounted on the shaft 115 so as to permit manual operation of the volume control.

On the side of the casting 83 adjacent the flange 105 on the end of the stub shaft 104, there is secured a switch 122 having a movable element 123 and a stationary element 124. The switch is secured to the casting by machine screws 125 and insulated therefrom by insulating strips 126. The movable member 123 lies across a continuation of the rod

- 107 and has an insulating abutment 127 in close proximity to the end of the rod. The switch is normally closed and is opened by movement of the rod 107 caused by the movement of the disc 100 to connect the shaft 60 to the shaft 86. Thus, the switch is opened whenever the motor is connected to the transmission mechanism of the automatic tuning device.
- 10 The electrical circuits and the mechanism for controlling the motor from the remote point will now be described. The controller box and mechanism which are situated at a remote point, are illustrated in Figs. 10 to 15 inclusive. The box has a cast back 128 and a cast cover 129 constituting the sides and front with an outlet for a cable in an end wall. The cover 129 is secured to the back 128 by screws 130. Near one end of the cast bottom at the longitudinal center thereof, a stub shaft 131 is rotatably mounted therein and extends perpendicularly therefrom. On the shaft 131 there is slidably mounted a casting 132 which extends through the top of the control box. Near the upper end of the casting 132, upwardly extending parallel projections 133 are formed which are adapted to be received in depressions 134 on the inner surface of the top of the control box. At the lower end of the casting 132, there is provided a groove 135 which houses a convolute spring 136 which resiliently urges the casting 132 toward the top of the control box and retains the projections 133 in the depressions 134. A portion of the outer wall of the spring housing 135 is extended to form a downwardly extending projection 137 which is adapted to register with openings 138 in the back of the control box. Movement of the casting 132 in a longitudinal direction is limited by a machine screw 139 engaging a groove 140 in the shaft 131. On the end of the casting 132 extending above the top of the control box, there is secured a knob 141 having a radial indicating pointer 142. In the top of the box, there is also a plurality of equally spaced radial slots 143, shown as ten in number, disposed about the center of the knob 141. Beneath the slots 50 are placed transparent strips 144 upon which the call letters of the various broadcasting stations are indicated corresponding to the call letters on the strip on the front panel of the receiving set. The depressions 134 in the inner surface of the top of the box and the openings 138 in the back of the box are in alignment and correspond to the slots in which the station indicating strips are placed.
- The electrical circuits are so arranged that 60 when the operator rotates the casting 132 into register with any one of the stations indicated on the strips in the slots 143 and presses down on the knob to move the casting against the action of the spring 136, a solenoid 69 corresponding to the said station will be energized and attract its lever into the path of the casting 31, and the motor will be energized simultaneously. This is effected through a series of switches against the back 128 of the box. As shown there are two series of switches, a bottom series 145 which is a circular conducting bar having ten individual radial contact strips; and an upper series 146 of ten separate and insulated radial strips. The two series are disposed in pairs, one immediately above the other, and the depression of the knob 141 serves, through the medium of a radial projection 147 in alignment with the pointer 142 and carrying a knob 148 of insulating material, to move the contact point of the strip 146 with which it registers into contact with the contact point on the strip 145 immediately below it, and a continued movement of the knob 141 presses the lower contact strip against a contact point on a circular bar 149 which runs underneath all of the contacts. Lamps 150 and 151 are supported on a bracket upon the side wall of the box immediately behind a red lens 152 and a green lens 153 in the front face. Two volume control switches are also provided, one for increasing the volume and the other for decreasing the volume. Both of the volume control switches are double throw switches, one having a single pole and the other having three poles. The three pole switch consists of three sets of three separate contact strips 154, 155 and 156 disposed one immediately below the other, the intermediate set 155 being extended beyond the ends of the upper and lower sets and having an insulating cross bar 157 connecting them together for simultaneous mechanical movement. Normally, the intermediate set is in contact with the upper set and is depressed into contact with the lower set by a rod 158 extending through a bushing 159 formed on the inner side of the front face of the control box. The rod 158 is aligned with the insulating cross bar 157 connecting the outer ends of the middle strip and has a knob 160 secured to the end extending above the front face of the control box. The rod 158 is resiliently urged to the inoperative position by a convolute spring 161. The single pole volume control switch is similar in all respects to the three pole switch just described having three contact strips 162, 163 and 164 disposed one immediately above the other. A two way switch 165 is also provided in the front wall of the control box.
- The electrical connections for the remote control of the automatic tuner are shown diagrammatically in Figure 16, the connections being as follows:
- A 110-6-18 volt transformer 166 and the receiving set are connected in multiple to the line wires 167 and 168, the connection being completed through a two way switch 169 at the set and the two way switch 165 at the remote control box. There is also a

master switch 170 connected in multiple with the two way switches 169 and 165 to complete the circuit to the set and the transformer independently of the two way switches. The 5 secondary side of the transformer constitutes the source of energy for the remote control mechanism. The transformer has two taps, one of which supplies six volts and the other eighteen volts. The side of the transformer 10 common to the six and eighteen volt taps is connected by means of a wire 171 to a wire 172 in the remote control box. To the wire 172, which is common to the lower contact strip 156r at the right of the three pole double 15 throw switch and the lower contact strip 164 of the single pole double throw switch at the remote control box, one side of the lights 150 and 151 and the contact strips 145 are connected. The other side of the light 20 150 is directly connected by a wire 173 to the six volt tap on the transformer. Thus, the light 150 is directly connected to the transformer and is energized whenever the transformer is operating to indicate when the receiving set is turned on. The other side of 25 the light 151 is connected to the six volt tap of the transformer through the switch 76 on the side frame member 11 which is actuated by the longitudinal movement of the square shaft 75 to complete the connection to the light 151 when the set has been tuned by the automatic tuning device. The eighteen volt tap of the transformer is connected to one 30 side of the field 174 of the motor 59 by a wire 175. One side of each of the solenoids 69 is connected in multiple through a contact bar 175a which is connected to the wire 175 through the wire 176. The other sides 35 of the solenoids 69 are connected through individual contacts 177 to the individual contact strips 146 at the remote control box. To the side of the field of the motor to which the wire 175 is connected, one side of a rectifier 178 is also connected. The rectifier is 40 adapted to supply direct current to the coil 89 of the magnetic clutch to which it is connected by means of wires 179 and 180 through the brush contacts 95 and the collector rings 92 and 93. The opposite side of the field 45 174 of the motor is connected by means of a wire 181 to the intermediate contact strips 155-1 at the left of the double throw three pole switch at the remote control box, two poles 155-1 and 155c of which constitute a 50 reversing switch, the upper contact strips 154-1 and 154c being connected by means of wires 182 and 183 to the armature 184 of the motor and the lower contacts 156-1 and 156c being connected to the upper contacts 55 154-1 and 154c by cross wires 185 and 186. The upper contact 154r of the remaining pole of the three pole switch is connected by means of a wire 187 to the alternating current side 60 of the rectifier 178. The intermediate contact strip 155c of the reversing switch is con- 65

nected by a wire 188 to the central contact strip 163 of the single pole double throw switch and to the contact bar 149. The remaining central contact strip 155r of the three pole double throw switch is connected by 70 means of a wire 189 to the upper contact strip 162 of the single pole double throw switch. Thus, it will be seen that when the transformer is energized and the knob 141 is depressed to bring the contact strips 145, 146 75 into contact with the contact bar 149, the solenoid 69 associated with the contact 145 so depressed will be energized by a circuit as follows:

From the transformer through wire 171 to wire 172, thence through contact strips 146 and 145 to the solenoid 69 and through wires 176 and 175 to the opposite side of the transformer thereby energizing the solenoid which operates to raise the abutment lever 80 associated therewith into the path of the casting 31. Further depression of the knob 141 to depress the contact strip 145 into contact with the contact bar 149, completes a circuit to the motor and magnetic clutch as 85 follows:

To contact strip 145 as before, through contact bar 149, and wire 188 to intermediate contact strip 155c of the reversing switch, through the upper contact strip 154c of the reversing switch, and wire 183 to armature 184 of the motor through the armature, wire 182, upper contact strip 154-1 of the reversing switch, intermediate contact strip 155-1, wire 181, motor field 174 and wire 175 back 90 to the transformer. A second circuit is also completed through the intermediate contact strip 163 of the single pole double throw switch, upper contact 162, wire 189 to the intermediate contact strip 155r of the three pole double throw switch through the switch to wire 187, and the rectifier 178 to wire 175 and back to the transformer. Thus, a circuit 95 is completed to energize the magnetic clutch, thereby connecting the motor to operate the automatic tuning mechanism. 100

The volume is varied by depressing either of the volume switches. If the single pole double throw volume switch is depressed a circuit will be completed to the motor as follows:

To wire 172 as before, through lower contact strip 164 of the single pole double throw switch intermediate contact strip 163, wire 188, intermediate central contact strip 155c of the reversing switch, wire 183, motor armature 184 and wire 181 to the field of the motor, and thence through wire 175 to the transformer. It is to be noted that on depressing the single pole double throw switch the circuit to the magnet clutch is broken between the wires 188 and 189 thereby leaving the motor disconnected from the tuning mechanism. To vary the volume in the opposite direction, the three pole double throw switch 115 120 125 130

is depressed thereby reversing the connections to the armature of the motor completing a circuit as follows:

From the transformer to wire 172 as before, the lower contact strip 156r of the three pole switch, through the intermediate contact strip 155r, wire 189, upper and intermediate contact strips 162 and 163 of the single pole double throw switch, wire 188, intermediate and lower contact strips 155c and 156c, wire 185, upper contact 154-1, wire 182, motor armature 184, wire 183, upper central contact strip 154c, wire 186, lower and intermediate contact strip 156-1 and 155-1, wire 181 to the field of the motor and back to the transformer as before, the circuit to the magnetic clutch being broken between upper and intermediate contact strips 154r and 155r.

20 The switch 122 operated by the magnetic clutch through the medium of the rod 107 is connected in the loud speaker circuit by means of the wires 190 and 191 so that when the magnetic clutch is energized, the switch 25 will be opened and the loud speaker shut off during the tuning of the receiving set.

From the above description of the electrical circuits, it will be apparent that upon pressing the knob 141, the solenoid 69 associated with the contact strip depressed will be energized to insert an abutment lever into the path of the casting 31, the electric motor 59 will be started and the magnetic clutch will be energized to connect the transmission 35 of the tuning mechanism to the motor and break the connection between the motor and the volume control and open the circuit to the loud speaker. When the tuning of the set is completed, the switch 76 is closed to 40 complete the circuit to the signal lamp 150 at the remote control box, and in response to the signal, the operator releases the knob 141 permitting the various devices to return to their normal positions. On actuating the 45 single pole volume control switch, the motor is operated in one direction to increase the volume, and actuation of the three pole volume control switch operates the motor in the opposite direction to decrease the volume, 50 the magnetic clutch remaining deenergized and the motor and the transmission mechanism of the automatic tuner being disconnected.

It is obvious that various changes may 55 be made in the illustrated embodiment of my invention particularly described above within the principle and scope of my invention as expressed in the appended claims.

I claim:

60 1. In a radio receiving set, a movable member operatively connected to a tuning element of the set, a motor, a plurality of actuating members for the movable member having adjustable connection therewith, a single operating member for the several actuating

members shiftable selectively into engagement therewith, operating means for effecting the shifting and operation of said operating member, and a magnetic clutch for controlling the connection of the motor to said 70 operating means.

2. In a radio receiving set, a movable member operatively connected to a tuning element of the set, a motor, a plurality of actuating members for the movable member having adjustable connection therewith, a single operating member for the several actuating members shiftable selectively into engagement therewith, operating means for effecting the shifting and operation of said operating member, an electromagnetic clutch for controlling the connection of the motor to said operating means, and manually controlled means for energizing the magnetic clutch.

3. In a radio receiving set, a movable member operatively connected to a tuning element of the set, a motor, a plurality of actuating members for the movable member having adjustable connection therewith, a single operating member for the several actuating members shiftable selectively into engagement therewith, operating means for effecting the shifting and operation of said operating member, an electromagnetic clutch for controlling the connection of the motor to said operating means, and a manual switch device controlling the energization of the magnetic clutch and the motor.

4. In a radio receiving set, a movable member operatively connected to affect the volume of the sound emitted, another movable member operatively connected to a tuning element of the set, a plurality of actuating members for the second mentioned movable member having adjustable connection therewith, a power device selectively connectible to the several actuating members and the first mentioned movable member to operate the same, and manually controlled means for selectively connecting the power device to the several actuating members and the first mentioned movable member.

5. In a radio receiving set, a movable member operatively connected to affect the volume of the sound emitted, another movable member operatively connected to a tuning element of the set, a plurality of actuating members for the second mentioned movable member having adjustable connection therewith, an electric motor, means for selectively connecting the motor to the several actuating means and the first mentioned movable member, and a manual switch device controlling the operative connection and the energization of the motor.

6. In a radio receiving set, a movable member operatively connected to affect the volume of the sound emitted, another movable member operatively connected to a tuning ele-

- ment of the set, a plurality of actuating members for the second mentioned movable member having adjustable connection therewith, manually operable means for selectively operating the actuating members, additional manually operable means for operating the first mentioned movable member, an electric motor selectively connectible to operate the manually operable means for the actuating members and the manually operable means for the first mentioned movable member, and a manual switch device controlling the operative connection of the motor and manually operative means for the actuating members and energizing the motor.
7. In a radio receiving set, a movable member operatively connected to affect the volume of the sound emitted, said movable member being movable in one direction to increase the volume of the sound emitted, and in the opposite direction to decrease the volume of the sound emitted, manually operable means for the movable member, another movable member operatively connected to a tuning element of the set, a plurality of actuating members for the second mentioned movable member having adjustable connection therewith, manually operable means for selectively operating the actuating members, an electric motor selectively connectible to operate the manually operable means for the actuating members and the manually operable means for the first mentioned movable member, and a manual switch device controlling the operative connection of the motor, the manually operative means for the actuating members and the direction of movement of the first mentioned movable means, and energizing the motor.
8. In a radio receiving set, a movable member operatively connected to affect the volume of the sound emitted, another movable member operatively connected to a tuning element of the set, a plurality of actuating members for the second mentioned movable member having adjustable connection therewith, operating means for the several actuating members, an electric motor, an electromagnetic clutch for selectively connecting the motor to said first movable member and said operating means for the actuating members, and a manual switch device controlling the magnetic clutch and the energization of the motor.
9. In a radio receiving set, loud speaker connections, a movable member operatively connected to a tuning element of the set, a plurality of actuating members for the movable member having adjustable connection therewith, an operating member selectively connectible to the several actuating members to operate the same, a power device connectible to the operating member for operation thereof, and means operative in response to the connecting of the power device to the operating member for affecting the loud speaker

connection to cut out the loud speaker during operation of the operating member by the power device.

10. In a radio receiving set, loud speaker connections, a movable member operatively connected to a tuning element of the set, a plurality of actuating members for the movable member having adjustable connection therewith, a power device selectively connectible to the several actuating members to operate the same, manually controlled means for selectively connecting the power device to the several actuating members, and means operative in response to the connection of the power device to operate the actuating members for affecting the loud speaker connections to cut out the loud speaker during operation of the actuating members.

11. In a radio receiving set, loud speaker connections, a movable member operatively connected to a tuning element of the set, a plurality of actuating members for the movable member having adjustable connection therewith, a single operating member for the several actuating members shiftable selectively into engagement therewith, operating means for effecting the shifting and operation of said operating member, an electric motor, a clutch for controlling the connecting of the motor to said operating means, and means operative in conjunction with the clutch for affecting the loud speaker connections to cut out the loud speaker while the motor is connected to the operating means.

12. In a radio receiving set, loud speaker connections, a movable member operatively connected to affect the volume of the sound emitted, another movable member operatively connected to a tuning element of the set, a plurality of actuating members for the second mentioned movable member having adjustable connection therewith, a single operating member for the several actuating members shiftable selectively into engagement therewith, operating means for effecting the shifting and operation of said operating member, an electric motor, a clutch for selectively connecting the motor to the operating means and the first mentioned movable member, means for controlling the action of the clutch, and the energization of the motor, and means operative in conjunction with the clutch for affecting the loud speaker connections to cut out the loud speaker while the motor is connected to the operating means.

13. In a radio receiving set, loud speaker connections, a movable member operatively connected to affect the volume of the sound emitted, another movable member operatively connected to a tuning element of the set, a plurality of actuating members for the second mentioned movable member having adjustable connection therewith, a single operating member for the several actuating members shiftable selectively into engage-

ment therewith, operating means for effecting the shifting and operation of said operating member, an electric motor, an electro-magnetic clutch for selectively connecting the motor to the operating means and the first mentioned movable member, a manually operable switch device for controlling the action of the clutch and the energization of the motor, and means operative in conjunction with the clutch for affecting the loud speaker connections to cut out the loud speaker while the motor is connected to the operating means.

14. In a radio receiving set, a tuning device comprising a movable member operatively connected to a tuning element of the set, a plurality of actuating members for the movable member having adjustable connection therewith, a single operating member for the several actuating members shiftable selectively into engagement therewith, a shaft journaled at one end in the tuning device and threaded in the tuning device at the other end, whereby rotation of the shaft causes longitudinal movement thereof, a pinion splined on the shaft operatively associated with the operating member for the actuating members, a switch in the path of the longitudinal movement of the shaft, a pilot light associated with the switch to be energized by the closing thereof, and an electric motor operatively related to the operating member for the actuating members.

15. In a radio receiving set, a tuning device comprising a movable member operatively connected to a tuning element of the set, a plurality of actuating members for the movable member having adjustable connection therewith, a single operating member for the several actuating members shiftable selectively into engagement therewith, an operating pinion connected to the operating member for operation thereof and secured to the operating member against relative lateral movement therebetween, a screw shaft extending through the operating pinion and journaled in the tuning device so as to prevent axial movement thereof, internal projections on the operating pinion engaging the threads in the screw shaft for first advancing the operating member into its selective engagement with the actuating member upon rotation of the screw shaft and then frictionally engaging the sides of the threads in the shaft to rotate the pinion therewith for operation of the operating member, another shaft journaled at one end in the tuning device and threaded in the tuning device at the other end so that rotational movement of the shaft is translated into longitudinal movement thereof, a pinion splined on the second mentioned shaft operatively connected to the pinion on the screw shaft, a switch in the path of the longitudinal movement of the second mentioned shaft, a pilot light connected to

the switch to be energized by the closing thereof, and an electric motor operatively related to the operating member.

In witness whereof, I hereunto subscribe my signature.

LOUIS H. MORIN.
